6 Claims. (Cl. 66—96)

This invention relates to improvements in the manufacture of knitted goods on the straight bar knitting machine, in which loop transfer takes place within the width of the fabric.

If, in the production of fabric, for example footwear, loops have to be transferred on to adjacent needles on which loops are worked or reinforced by special threads, then, during transfer, the thread, which serves for the production or reinforcing of adjacent loops, is taken along by the transfer points through the number of loops to be transferred, because the corresponding thread guide is not displaced therewith in the transferring operation, as is the case in narrowing for example. The result of this is that the thread is pulled out of the thread guide and is brought into a wrong position in relation to the selvedge needle of the part of the work that is made or reinforced with special threads, on which needle the adjacent loops of the portion of the work that lies further inwards are covered. The thread is thus brought into a wrong position in relation to the sinkers and is seized by the wrong sicker when the sinkers proceed to sinking and dividing. The result of this is that large and loose selvedge loops are formed which are disadvantageous to the appearance of the goods.

According to the invention, the formation of loose selvedge loops is avoided by shortening the nebs or nebs of the dividing sicker or sinkers of the flat knitting machine which is or are associated with the selvedge needle or selvedge needles of the portion of the work which is made or reinforced with a special thread. The number of the dividing sinkers depends, in this case, on the number of loops which are to be covered.

As already mentioned, the invention is also applicable to the method for the production of hosiery in which heel parts are subsequently joined to connectedly worked pieces of hosiery consisting of legs and feet and the initial rows of the side parts of the feet, which are likewise run on to the needle row of the knitting machine, are connected with the inner selvedge loops of the heel parts by consecutive widening. In carrying out this method, operations in which rows of heel loops are formed alternate with transfer operations in which loops of the side parts of the foot are transferred to the selvedge needles of the, for the time being, newly formed heel row. In this case also, the thread for the production of the heel parts is taken along through the number of loops that are to be covered and is pulled out of the thread guide by

the outside needle of the transfer device. This can be avoided if the nebs of the sinkers that are adjacent to the selvedge needles of the heel parts are shortened.

5 The improvement can also be employed with advantage in the case of knitting machines with patterning devices, for example, knitting machines with a lace attachment.

The invention will now be explained with the aid of the drawing:

In the drawing,

Figs. 1 to 3 show how displacement of the thread takes place in the transfer operation with the usual construction of sinkers of the 15 straight bar knitting machine.

Fig. 4 shows the construction of the sinkers according to the invention and the resulting thread guidance and

Fig. 5 is a view of part of the shortened sicker.

In the drawing, only a few needles of the needle bar of the straight bar knitting machine are shewn together with the front ends of the sinkers and a few covering needles with a part of the covering needle-bar. The knitting machine itself is not shown, since it is an ordinary knitting machine in which the needles, sinkers and transfer points are actuated in the known manner.

On the needles 1, 1a and 1b, there are located loops of a portion of work which is made with a thread 5 and with the corresponding thread guide 6. On the left of the needles 1, there lie the needles 2, 2a and 2b of the needle bar, on which needles another part of the work is made with another thread guide and with another thread 3. In order easily to distinguish the threads, the thread 3 has been shown thin and the thread 5 has been shown thick. The loops 4 are sunk toward the middle of the work. The thread guide 6, in this case, arrives in the position represented in Fig. 1. Now, it is assumed that three loops of the inner portion of the work are transferred by the three transfer points 1, 1a and 1b through two wales towards the right, so that the loops of the needle 2 come to lie on the needle 1a, those of the needle 2a are brought on to the needle 1 and those of the needle 2b on to the needle 2. This transfer may be effected for the purpose, for example, of patterning the fabric. In this case, the thread 5 is, as a rule, a reinforcing thread and the loops on the needles 1, 1a, and 1b are sunk from the thread 3 or, in the case of a heel frame, the transfer can be effected for the purpose of obtaining a connection of the loops 3 with the loops 4.

As shown in Fig. 1, the thread 5 is taken along with the transfer point 7, so that the thread now places itself around the needle 1a. In Fig. 2, there is shown the position of the sinkers—i. e. the dividing sinkers V₁, V₂ and jack sinkers K₁, K₂—after the completion of the transfer operation. The transfer points 7, 7a and 7b have been returned to their position of rest. As shown in Fig. 2, the thread 5 is now held fast by the dividing sinker V₂. If the thread guide 6 is now moved to the right after the upward movement of the frame needles, the thread forms round the needle 1 a loop which results in a loose selvedge loop.

Fig. 4 shows the position when, according to the invention, the sinker which is adjacent to the needle 1 has been shortened to such an extent that the neb of this sinker can hold fast the thread displaced by the transfer point. On the movement of the thread guide 6, the thread which has been pulled out of the thread guide by the covering needle is now first again pulled up and places itself around the selvedge needles only as desired, i. e. the thread takes up the position that is necessary for the formation of tight selvedge loops.

This operation will be described more particularly in connection with the usual operation of the needles, transfer points, sinkers and dividers during a loop transfer operation as follows:

The carrier tube 6 prior to the coming down of the loop lifting points 7 in the Fig. 1 position, comes to rest over the divider V¹, the yarn 5 extending from the fabric to the carrier tube from the left-hand side of the needle 1 over the top of the sinker K¹, as the loop lifting points 7 are moved down between the sinkers prior to their two-needle shift to the right, the point 7 is in line with the needle 2 and therefore causes the yarn 5 to lay to the right of the point 7. As the loop lifting points are shifted to the right two indexes, so that the point 7 is in line with the needle 1a, which is in the position the points are shown in Fig. 1, the yarn 5 between the carrier tube 6 and the fabric, is shifted with the point 7 and the leading transferred loop to the right as shown in Fig. 1, it being understood that this shifting of the loop lifting points takes place as in ordinary Cotton type machines, with the entire fabric well above all the sinker noses so that the said noses cannot interfere with the shifting of the fabric and the shifting of the yarn 5. After the narrowing points transfer their loops to the needles, the fabric is again, as in ordinary Cotton machine practice, brought down under the sinker noses and the sinkers and dividers are brought forward so that if the divider V² has an ordinary long nose as shown in Fig. 2, the yarn 5 will be left wrapped around the nose of this divider as shown in Fig. 2, but due to the incoming of all the jack sinkers, more particularly sinkers K¹ (Fig. 2), the yarn 5 is as in ordinary Cotton practice, positioned by the throat of this sinker K¹ to the back side of the needle, so that as the needles rise, the yarn is wrapped around the needle 1 as is necessary, but instead of it being wrapped around this needle under the sinker noses, it is wrapped around this needle by reason of the fact that the yarn 5 lies over the top of the nose of the divider V² above the sinker noses as shown in Fig. 3, thereby forming a very undesirable loose loop at the reversal, whereas if the divider V² has a neb short enough so that its forward end is somewhat to the back of the back shank of the needle (beard shank side of the

needle), the yarn 6 instead of remaining hung on the nose of the V² divider will fall off and so not form the undesirable yarn loop, as clearly shown in Fig. 4.

A short neb is used only on the divider because undesirable loops are not formed by the long-nosed jack sinkers, and also because the jack sinker nose at a knitting juncture, as for instance the sinker K¹ (Fig. 1) must have a nose long enough to reach through the needles so that the yarn running to the last needle through the carrier tube 6 at the time the yarn loops are drawn off the sinker noses during the normal process of knitting, will remain on top of the jack sinker neb of the jack sinker immediately to the right of the last active needle, as otherwise the yarn upon reversal, as for instance in the Fig. 4 position, would wrap around the outside nose, or if it were short enough, the jack sinker K² (Fig. 4) would not elevate the yarn high enough to permit this and succeeding jack sinkers to properly form the next course of kinks.

Fig. 5 shows a view of the front end of the sinker V₂. The number and kind of sinkers to be shortened depends upon the position of the sinkers in relation to the corresponding selvedge needles and upon the number of loops to be transferred.

We claim:

1. In a knitting machine, knitting instrumentalities including a needle series, jack and dividing sinkers, a yarn carrier and loop lifting points arranged to shift certain of the loops of the fabric and transfer the same to adjacent needles whereby the yarn between the carrier tube and the fabric is lengthened, said knitting instrumentalities being constructed and arranged to cause the yarn extending between the carrier tube and the fabric to shorten its length to normal prior to the next Coulier action of the sinkers.

2. In a knitting machine, knitting instrumentalities including a needle series, jack and dividing sinkers, yarn feeding means, loop lifting points arranged to shift certain of the loops of the fabric and transfer the same to adjacent needles whereby the yarn between the carrier tube and fabric is lengthened, a carrier arranged to feed yarn to certain of the needles only, said knitting instrumentalities being constructed and arranged to cause the yarn extending between the carrier tube and the fabric to shorten its length to normal prior to the next Coulier action of the sinkers.

3. In a straight bar knitting machine having knitting instrumentalities including a needle series, jack and dividing sinkers, a yarn carrier arranged to feed yarn to certain only of the needles forming an inner selvage edge, and loop lifting points arranged to shift certain of the loops of the fabric and transfer the same to adjacent needles including a needle forming said inner selvage edge whereby the yarn between the carrier tube and fabric is lengthened, the jack sinkers having nebs of sufficient length to extend between the needles, and the dividing sinker associated with the inner selvage needle having a shorter neb to permit unobstructed passage between said latter neb and the needle series of the feeding yarn extending from the carrier and displaced with the transferred loops.

4. In a straight bar knitting machine having knitting instrumentalities including a needle series, jack and dividing sinkers, a yarn carrier arranged to feed yarn to certain only of the

needles forming an inner selvage edge, and loop lifting points arranged to shift certain of the loops of the fabric and transfer the same to adjacent needles including a needle forming said inner selvage edge whereby the yarn between the carrier tube and fabric is lengthened, certain of the dividing sinkers having a neb of a less than normal length to permit unobstructed passage between the neb and the needle series of the feeding yarn extending from the carrier and displaced with the transferred loops, said certain sinker being located between the inner selvage needle and the needle on which the transferred loop carrying with it the displaced feeding yarn is placed.

5. In a straight bar knitting machine having knitting instrumentalities including a needle series, jack and dividing sinkers, yarn feeding means including a yarn carrier arranged to cooperate with any designated intermediate needle of the series to form an internal selvage, and loop lifting points arranged to transfer onto said inner selvage and adjoining needles, fabric loops held on needles adjacent to said selvage needle and formed with a different knitting yarn, certain of the dividing sinkers having a neb of less than normal length to permit unobstructed pas-

sage between the neb and the needle series of the feeding yarn extending from the carrier and displaced with the transferred loops, said certain sinker being located between a designated selvage needle and the needle on which the transferred loop carrying with it the displaced feeding yarn is placed.

10 6. In a straight bar knitting machine having knitting instrumentalities including a needle series, jack and dividing sinkers, yarn feeding means including a yarn carrier arranged to cooperate with an intermediate needle of the series to form an internal fabric selvage with respect to fabric loops formed of a different knitting 15 yarn and held on adjacent needles, and loop lifting points arranged to shift said adjacent fabric loops formed with the different knitting yarn and transfer the same to said selvage and adjoining needles to form a juncture between the two sets 20 of loops, the dividing sinker located between the selvage and adjoining needle having a short neb to permit unobstructed passage between the neb and the needle series of the feeding yarn extending from the carrier and displaced with the transferred loops.
